UNITED STATES PATENT OFFICE.

ROY L. BOSWELL AND HARRY E. MARTIN, OF TATE, NEBRASKA.

COLLAPSIBLE SHIPPING-CASE.

1,228,287.

Specification of Letters Patent. Patented May 29, 1917.

Application filed July 10, 1916. Serial No. 108,393.

To all whom it may concern:

Be it known that we, ROY L. BOSWELL and HARRY E. MARTIN, citizens of the United States, residing at Tate, in the county of Pawnee, State of Nebraska, have invented certain new and useful Improvements in Collapsible Shipping-Cases; and we do hereby declare the following to be a full, clear, and exact description of the invention, such as will enable others skilled in the art to which it appertains to make and use the same.

This invention relates to improvements in shipping receptacles, and is directed more particularly to collapsible cases adapted for use in the transportation of eggs or other articles.

An object of the present invention resides in the provision of a collapsible shipping case embodying means of novel construction and arrangement for securing it in set-up position.

A further object of the invention is to provide a case which may be conveniently folded in small compass for storage or shipment.

The invention further proposes a fastening means of novel construction and application for assembling the various portions of the case.

With the above and other objects of similar nature in view, the invention consists in the construction, combination and arrangement of parts, set forth in and falling within the scope of the appended claims.

In the drawing:

Figure 1 is a plan view of the blank from which our improved case is formed;

Fig. 2 is a perspective view of the case illustrating the manner of assembling the same;

Fig. 3 is a plan view of the case in set-up position;

Fig. 4 is a transverse section taken on the line 4—4 of Fig. 2;

Fig. 5 is a detail section taken on the line 5—5 of Fig. 5;

Fig. 6 is a detail perspective view of one of the fastening devices;

Fig. 7 is a horizontal section through the case with the partition and strengthening member in place; and

Fig. 8 is a detail perspective view of one of the elements of said member, the other element being indicated in dotted lines as interlocked therewith to illustrate the posi-

tion assumed by the parts when placed in the case.

Referring now more particularly to the accompanying drawing, there is illustrated in Fig. 1 the blank from which our improved case is formed, said blank consisting of a substantially rectangular body 10 provided with parallel fold lines 11 dividing the body into a central portion adapted to form the bottom 12 of the case and side portions adapted to be disposed at right angles to the central portion to provide the side walls 13 of the case.

Formed at the ends of the side portions 13 and defined therefrom by the fold lines 14, are flaps 15 adapted to be folded to lie in overlapped relation to provide the ends of the case. Certain of these flaps are provided with spaced series of openings 16 while the remaining flaps are provided with spaced pairs of openings 17. In folding the end flaps to form the ends of the case, those provided with the openings 16 are disposed inwardly of those having the openings 17, while the latter openings are disposed in registration with corresponding pairs of openings 16.

Formed at the ends of the central portion 12 of the body and defined therefrom by the fold lines 18, are flaps 19 foldable to overlap the end flaps 15 and provided with spaced pairs of elongated openings 20 registerable with the corresponding openings in said flaps. Formed on the outer transverse edge portions of the flaps 19 and defined therefrom by the fold lines 21 are flaps 22, foldable to close the top of the case. Formed on the outer longitudinal edges of the side portions 13 and defined therefrom by the fold lines 23, are flaps 24 foldable to overlap the flaps 22.

These flaps 24 are similarly provided adjacent their ends with elongated openings 25, aligned transversely in pairs when the case is assembled.

With the case in set-up position, in order to secure together the end flaps 15 and flaps 19, there are provided flexible strips 26 intermediately bent with their ends inserted inwardly through the registering openings 20, 17 and 16. It will be noted that the end 27 of each of the strips is of a length greater than the end 28 thereof, and that after inserting said ends through the registering openings they are bent toward each other to securely retain the flaps in their relative

positions, the end 27 being disposed to overlie the end 28 and continued therebeyond for insertion in the lower of the openings 16 in the related series. The flaps are thus held 5 against accidental displacement, while to collapse the case said strips may be conveniently disengaged from the flaps by reversing the above described operation.

Connecting the strips 26 at each end of the 10 case, is a bar 29 secured as at 30 to the intermediate portions of the strips, and constituting a suitable handle by which the case may be conveniently carried when in set-up position. For dividing the case into compartments as illustrated in Fig. 7 of the 15 drawing, there is provided a combined partition and strengthening member 33 consisting preferably of two similarly formed strips 34 of fiber or pulp board interlocked 20 one with the other. The intermediate portion 35 of each strip is slotted transversely from one side as indicated at 36 while its ends 37 are bent oppositely at right angles from the intermediate portion. In assembling 25 the strips, the intermediate or slotted portions are disposed with the slots 36 opening toward each other and are brought together in interlocked relation as shown most clearly in Fig. 8. The intermediate portions 35 thus provide the partition which divides the case into compartments while the 30 ends 37 of each strip coöperate with the adjacent ends of the other strip to reinforce the side walls of the compartments thus produced. The eggs will in this manner be 35 protected on all sides by a double thickness of board, possibility of breakage being correspondingly reduced, while the case itself will be materially strengthened to resist the 40 hard usage to which it may be subjected. With the partition and strengthening member in position, suitable fillers and flats (not shown) may be placed in the case and filled 45 with eggs in the usual manner after which the flaps 22 and 24 are folded to close the case.

In order to lock the case, there is carried by each of the flaps 22, a strip 31 intermediate secured to the flap as at 32, with its 50 ends bent upward and adapted for insertion through corresponding openings 25. After insertion of said ends through the openings, they are bent toward each other as clearly illustrated, one of said ends being longer 55 than the other and adapted to overlie the same with its terminal removably inserted in the related opening of the shorter end.

Thus in order to gain access to the case, it is only necessary to withdraw the longer 60 end from the opening and then bend the end

upwardly to permit of disengagement of the flaps 24.

What is claimed is:

1. In a collapsible shipping case, the combination with overlapping flaps providing a 65 wall of the case, said flaps having pairs of registering openings, and one of the flaps being further formed with an opening in vertical alignment with said registering openings, of a locking strip having its ends 70 bent and inserted through the registering openings, one of said ends being further bent to overlie the other end thereof and extending therebeyond and entering the aligning opening with its extremity disposed between the flaps. 75

2. A collapsible shipping case including bottom, side and end walls, flaps carried by the end walls removably folded to close the 80 top of the case, flaps carried by the side walls removably folded to overlap the first named flaps and provided with transversely aligned openings and flexible locking strips secured between their ends to the first named flaps and having their ends removably inserted through corresponding openings in the last named flaps, one end of each strip being bent to overlie the other end thereof and having its extremity disposed in the 85 opening through which the other end protrudes. 90

3. A collapsible shipping case including bottom and side walls, flaps on the side walls folded in overlapped relation to close an end 95 of the case, a flap on the bottom wall folded in overlapped relation to the end flaps, a pair of locking strips having their ends removably engaged through and bent to lock together said end flaps and bottom wall flap, and a member connecting the strips outwardly of the flaps and forming a handle 100 for the case. 105

4. In a shipping case, the combination with overlapping wall portions having registering openings therein, of a locking element including a handle portion and spaced flexible strips connected by and secured between their ends to said handle portion, the ends of the strips being removably inserted through said registering openings and bent to lock said wall portions in overlapped relation. 110

In testimony whereof, we affix our signatures in the presence of two witnesses.

ROY L. BOSWELL.
HARRY E. MARTIN.
